UNITED STATES PATENT OFFICE

2,553,871

WRAPPING MACHINE

Oscar Sandberg, Toledo, Ohio, assignor to Lynch Corporation, Anderson, Ind., a corporation of Indiana

Application November 5, 1947, Serial No. 784,107

3 Claims. (Cl. 93—2)

1

This invention relates to a wrapping machine and particularly to means for properly holding the articles to be wrapped while lifting them upwardly into a wrapper folding head.

It is an object of the invention to provide supporting plates floatably carried by the pocket conveyor side plates and lifted by ram means, so that the supporting plates may be elevated up to a folder head and stopped while the ram continues to lift the article into the folder head.

It is another object of the invention to provide properly timed means which will lift article holding end plates toward a folding head and also to move a ram which lifts the articles into the pockets of the folding head.

It is also an object of the invention to provide for retaining the wrapping material in position with respect to the articles to be wrapped while the ram is lifting the articles into the folding head.

With these and other objects in view, the invention consists in the construction, arrangement and combination of the various parts of my device whereby the objects contemplated are attained, as hereinafter more fully set forth, pointed out in the claims, and illustrated in the accompanying drawings, wherein:

Figure 1 is a side elevation of a portion of a wrapping machine to which my present invention is applied;

Figure 2 is a diagrammatic elevation and plan view of the mechanism for retaining the wrapping material in position;

Figure 3 is a diagrammatic view of the mechanism shown in Figure 2, with the ram partially raised;

Figure 4 is a sectional view taken on line 4—4 of Figure 1;

Figure 5 is a partial sectional view taken on line 5—5 of Figure 1;

Figure 6 is a view similar to Figure 4, with the ram and the articles to be wrapped partially raised from the conveyor pockets;

Figure 7 is a partial sectional view similar to Figures 4 and 6, showing the ram, the articles to be wrapped and the floating side plates in their uppermost position; and

Figure 8 is an elevational view of a part of the mechanism for raising the floating side plates.

Referring specifically to the drawings for a detailed description of the invention, numerals 10 and 12 indicate supporting frame members for the wrapping machine. At the top of the frame members, a table 13 connects the frame

2

members together and provides a main support for parts of the machine.

The particular machine described is similar to the one shown in my copending applications, Serial No. 654,079, filed March 13, 1946, and Serial No. 712,970, filed November 29, 1946. Where practical, the same reference numerals have been applied as in the copending applications.

10 Pocket conveyor shafts 14 and 15 are suitably journaled in brackets 16 and 19 which extend from the frame member 10. The shafts carry sprockets 17 and 18, respectively. A pocket conveyor chain 20 surrounds the sprockets 17 and 18 and also a third sprocket (not shown) at the same elevation as the sprocket 17 and to the right of the drawing in Figure 1.

15 The conveyor chain 20 has spaced channel shaped article receiving pockets 25 mounted thereon. The pockets 25 are adapted to receive a stack of articles 26, such as cookies, crackers, or sandwiches of the type formed of two crackers with cheese or peanut butter between them. Several of the articles are arranged in a horizontal stack and in face to face relation in each pocket. Side bars 27 are located at each end of the stack to keep the cookies upright in the pockets until they reach a ram station over a ram head 40. The forward ends of the bars 27 are secured by rivets 22 to end plates 23.

20 The pocket conveyor 20—25 is driven by rotating the shaft 14 through a chain drive 28 from an intermittently driven shaft 29. The shaft 29 is driven through a Geneva movement including a notched disc 30 and a crank pin 32 which coacts with the notches. The crank pin 32 extends from a crank arm 33 which is secured to a shaft 34.

25 The shaft 34 is driven by a chain drive 35 from a main shaft 36 adjacent the lower part of Figure 1 through bevelled gears 37 and 38. The main shaft 36 is driven in any suitable manner, for example, from an electric motor through reduction gearing, such as shown in my Patent No. 2,283,097, issued May 12, 1942.

30 Each channel shaped pocket conveyor is provided with a rectangular opening 33 to permit the ram head 40 to pass up through the pocket. The ram head is on the upper end of a vertical ram post 41 secured to a slide 42 provided with four bearings 43. The bearings 43 slide on vertical guide rods 44 which are fixedly mounted with respect to the frame 10—12—13 by having their lower ends supported by the brackets 19 and their upper ends supported by brackets 16.

For vertically reciprocating the slide 42 and the ram post 41, I provide a link 48 pivoted to the slide and to an arm 49. The arm 49 is secured to a rock shaft 50 journalled in bearings 46 and 47 of the frame members 10 and 12. The rock shaft 50 has also secured thereto an arm 51 which is connected by a link 52 on a crank arm 53 on the main shaft 36. The main shaft 36 is rotated once each cycle of operation of the wrapping machine so that the ram head 40 is elevated and returned downwardly once each cycle and the Geneva movement disc 39 is advanced $\frac{1}{6}$ of a revolution each cycle. The advance of the Geneva disc 39 advances the pockets 25 one station each cycle and holds them at their stations, the ram station, of course, being the one in which the openings 39 of a pocket is directly above the ram head 40 so that the ram head may pass through the pocket.

Above the pocket 25, a folder head FH is provided. The folder head forms no part of the present invention, but is described in order to provide a complete operative machine. The folder head consists of a pair of stub shafts 55 on which a casting is mounted. The casting includes two end plates 56 and 57 with a connecting post 58 therebetween. At the center of the post 58, two cross passageways 59 are provided at right angles to each other, which result in the post 58 having four connecting portions 54.

Each end plate 56 and 57 has journalled therein a rod 60. It will be noted that four of the rods 60 are provided and that the folder head FH is arranged with four article receiving pockets, each formed by a flat plate 66 and arcuate plates 67 and 68. The plates 67 are fixed relative to the folder head and have eyes 69 loosely journalling the rods 60, so that the rods may rotate therein. The plates 66 are secured to the post sections 54, so that they are fixed with respect to the rotary folder head FH.

The folder head includes compression plates 271 and 272, one for each of the four pockets of the head. Each plate 271 is carried by a rod 273 which is fixed with respect to the folder head by being carried in the end plate 56. Each plate 272 is carried by a rod 274 which is slidable in the end plate 57 and is constrained to move in an inward direction by a spring 275. The inner limit of movement is determined by a stop collar 276 on the outer end of the rod 274 striking the end plate 57. The inner end of the spring 275 bears against a collar 277 on rod 274.

The stub shafts 55 are journalled in a bearing 72 on the left side of the machine and in a bearing 73 on the right side. The rotary folder head is periodically rotated $\frac{1}{4}$ of a revolution by means of gears 75 and 76 and a chain drive 77, which passes over an idler 74 from the shaft of the gear 76, to the shaft 29, the ratio being six to four, as the shaft 29 is rotated $\frac{1}{6}$ of a revolution each cycle and the folder head is rotated $\frac{1}{4}$ of a revolution each cycle.

With further reference to details of the folder head FH, means (not shown) is provided to automatically open the lowermost one of the pockets as the ram head 40 rises. This means consists of leverage mechanism, shown and described in my aforesaid copending applications. After the article and its wrapper have entered the pocket, the plate 68 is spring returned to closed position for retaining the partially wrapped package therein in cooperation with the plates 66 and 67.

A wrapper for wrapping the package is shown at 97 and is preferably supplied to the machine in roll form, the machine being provided with means to cut the strip from the roll into individual wrappers, as shown, for example, in my Patent No. 2,283,096 of May 12, 1942. The paper supply mechanism forms no part of the present invention, and, accordingly, is not illustrated herein.

10 The wrapper 97 is fed onto the table 13 in flat form beneath a pair of wrapper control rods 98 and 99. The rods are supported by a pair of supports 100. One of the rods is capable of slight floating movement horizontally, as its ends are mounted in horizontal slots 102 of the supports 100, and springs 105 normally bias the rod 99 toward the rod 98. The space between the rods is normally slightly less than the diameter of the article to be wrapped. The rods 20 thereby effect close engagement of the wrapper 97 around the stack of articles.

When the wrapper 97 is in the position shown in Figure 4, it is relatively flat, but as the ram head 40 rises, as shown in Figure 6, there is 25 sometimes a tendency for the wrapper to be displaced in one direction or another and result in an improperly wrapped package. This may be at least partially overcome by the hold-down mechanism shown in my copending application 30 Serial No. 712,970, or may be overcome by using the pocket construction for the folding head shown in my copending application Serial No. 769,618, filed August 20, 1947.

The machine is provided with an arm 157 at 35 the upper portion thereof, which is provided with a curved slot 156, best shown in Figure 1, in which a roller 154 is adapted to move. The roller 154 is mounted on a slide 155. The means for reciprocating the slide 155 comprises a pivot 40 146 on which the roller 154 is mounted and on which a fitting 144 is pivoted. Connected with the fitting 144 is a link 145 terminating at its forward end in a fitting 143 pivoted to a rock arm 147. The rock arm 147 is secured to a rock shaft 148, which is journalled in brackets 45 142 mounted on stationary rods 149 extending forwardly from the brackets 90.

Also secured to the rock shaft 148 is an arm 150 connected by a link 151 to a crank arm 50 153. The crank arm 153 is secured on the shaft 34 to rotate therewith. The crank arm carries a crank pin 152 on which the link 151 is rotatably mounted.

From the construction of the parts just described, it will be obvious that rotation of the shaft 34 in a clockwise direction will result in rotation of the crank pin 152 and thereby the rock shaft 148 is oscillated. Such oscillation is transformed into reciprocation of the slide 60 155 with the roller 154 reciprocating in a horizontal direction. It will be obvious that any movement to the left in Figure 1 will slightly raise the arm 157, whereas movement to the right will lower the arm 157.

65 The curvature of the slot 156 is such that considerable movement of the slide 155 and the roller 154 will result in much less oscillation of the bell crank 157-158 about its pivot 159 than the oscillation of the rock shaft 148. The purpose of this is so that a second slide 143, which is rotatable on horizontal guide bar 87, and is connected with the arm 158 by a link 186, will convey less movement than the slide 155, which carries a package pusher rod 171, the slide 143 70 carrying end folder plates 166. The rod 171

preferably splits into two bars 170, which terminate in pusher plates 172.

The parts which are associated with the ram 40 and adjacent parts of the machine for the purpose of the present invention will now be described. A cam track 106 is associated with and rotated continuously by the shaft 95. A roller 107 travels in the cam track 106, which roller 107 is secured to a lever 109 connected to a pivot shaft 108. A shorter link 110 is connected to the pivot shaft 108 and is pivotally connected at 111 to a vertical rod 112. The rod 112 is connected to one end 113 of a shaft 114, which is journalled at 115 in the frame member 10. A second crank element 117 is provided at the opposite end of the shaft 114 and is secured to a pair of forked vertically extending members 116. The vertically extending members extend outside of the pockets 25 and support article end supporting plates 119 through bracket members 120. The article end supporting plates 119 are bent to an inverted U-shape with the arms of the U on opposite sides of the plates 23, as best shown in Figures 4, 6 and 7. The plates 119 are, therefore, vertically movable in relation to the fixed plates 23. The plates 119 are, of course, limited in their movement by the crank arm 117.

The movement of the crank 113—114—117 is timed with respect to the ram 40, so that the ram moves upwardly first to start to raise the articles 26 to be wrapped above the level of the table 13, as shown in Figure 6. As the ram 40 moves upwardly, however, the side plates 119 also start to move upwardly, and when the ram has moved the articles to be wrapped completely into the pocket of the folding head, the side plates 119 have assumed the position shown in Figure 7. The side plates 119, therefore, prevent the articles to be wrapped from becoming disarranged or broken during the raising thereof by the ram into the pocket of the folding head. After the articles to be wrapped are in the pocket of the folding head, both the ram and the side plates 119 are returned to the position shown in Figure 1, whereupon the articles in the next pocket of the conveyor are moved between the plates 119.

It has been found that in some instances the wrapping material 97 is pulled more on one side of the articles than on the other as the ram 40 raises the articles into the pocket past the rods 98 and 99. I have, therefore, provided the following mechanism to hold the wrapping material in position with respect to the rod 98, since it is essential that sufficient wrapping material be provided at this portion of the article to insure that a fold may be made.

An ear 200 is provided below the table 13 to the left of the ram 40, as shown in Figures 1, 2 and 3. A lever 201 is pivoted centrally thereof at 202 on the ear 200. The lever 201 is pivotally connected to a second lever 204, which is in turn pivotally connected to a lever 206, which is pivoted at its center, as shown at 207, on a bracket 208. The levers 201 and 204 are provided with a pivot 203 and the levers 204 and 206 are provided with a roller 209 which rides on a second roller 210, which is rotated continuously by shaft 34. A cam surface 211 is provided on roller 210 to intermittently raise the lever arm 206, whereby the right hand end of the lever arm 201 will be moved upwardly. A spring 212 is provided for maintaining the roller 209 in contact with the roller 210, thereby retaining the right hand

end of the lever 201 normally in its lowermost position.

An L-shaped rod 213 is connected to the right hand end of lever 201 and extends upwardly 5 through an opening 214 in the table 13. As the ram 40 starts upwardly, the cam surface 211 is so positioned and timed that the rod 213 will move upwardly and engage the wrapping material 97 between the end of the rod 213 and the 10 wrapper control rod 98. This engagement continues until the ram and the articles reach approximately the position shown in Figure 3, whereupon the rod 213 is lowered. The mechanism, therefore, insures that the wrapping material will not slip past the control rod 98 during 15 a major portion of the travel of the articles into the pockets of the folding head.

Operation

In the operation of the wrapping machine, when the articles 26 reach the ram station, the ram head 40 will engage the articles and lift them, and at the same time, the end plates 119 will be raised to retain the articles in proper 25 relationship to enter the folding head. The control rods 98 and 99, and the mechanism which operates the rod 213, will insure that the wrapper is properly positioned and securely drawn against the articles to be wrapped while the ram head 40 and the side plates 119 are being elevated.

At the same time that the articles are being lifted into the folder head, the package pusher rod 171 is travelling to the left for expelling a previously partially wrapped package from that 35 pocket of the folder head which is adjacent the folding means 166. At the same time, the pusher plates 172 are pushing a partially wrapped article out of the folder head, the pocket plate 68 will be opened by suitable leverage means (not 40 shown) to release the article. Ram 40 and the side plates 119 are then moved downwardly, the pusher rod 171 is withdrawn and the folding head is turned another quarter of a revolution so that another pocket is available for receiving another 45 set of the articles to be wrapped.

From the foregoing description it will be obvious that I have provided an effective machine for controlling a stack of articles and a wrapper therefor from the time the article is lifted out 50 of the pocket conveyor until it is partially wrapped in a folder head. The parts are so designed and timed in their operating relation to each other that the wrapper is folded in the most efficient manner over the ends of the stack of articles. The folding operations may be completed in any manner well known in the art.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

65 I claim as my invention:

1. A wrapping machine comprising a feed conveyor for articles to be wrapped, which articles comprise a plurality of individual pieces disposed in face to face relationship, elevator means for 70 raising the article from the feed conveyor, means for raising and lowering the elevator means, a table above the elevator means having an opening therein through which the elevator means is adapted to pass, said table being adapted to receive a wrapper of sheet material above the open-

ing, a folder head above said table adapted to receive said article when it is raised by said elevator means, means for retaining the articles in face to face relationship while they are being raised into said folder head, means on two sides of said opening adapted to frictionally engage said wrapper sheet as the article is raised into the folder head and means for engaging one edge of the wrapper sheet between itself and one of said frictional engaging means to positively prevent movement of the wrapper sheet longitudinally at one edge thereof during said raising.

2. A wrapping machine comprising a feed conveyor for articles to be wrapped, which articles comprise a plurality of individual pieces disposed in face to face relationship, elevator means for raising the article from the feed conveyor, means for raising and lowering the elevator means, a table above the elevator means having an opening therein through which the elevator means is adapted to pass, said table being adapted to receive a wrapper of sheet material above the opening, a folder head above said table adapted to receive said article when it is raised by said elevator means, means for retaining the articles in face to face relationship while they are being raised into said folder head, means on two sides of said opening adapted to frictionally engage said wrapper sheet as the article is raised into the folder head and means for engaging one edge of the wrapper sheet between itself and one of said frictional engaging means to positively prevent movement of the wrapper sheet longitudinally at one edge thereof during said raising, said last means comprising a cam, an engaging member, and a linkage between the cam and engaging member for moving the engaging member into contact with one edge of the wrapper sheet.

3. A wrapping machine comprising a feed conveyor for articles to be wrapped, which articles comprise a plurality of individual pieces disposed in face to face relationship, elevator means for raising the article from the feed conveyor, means for raising and lowering the elevator means, a table above the elevator means having an opening therein through which the elevator means is adapted to pass, said table being adapted to receive a wrapper of sheet material above the opening, a folder head above said table adapted to receive said article when it is raised by said elevator means, means for retaining the articles in face to face relationship while they are being raised into said folder head, means on two sides of said opening adapted to frictionally engage said wrapper sheet as the article is raised into the folder head and means for engaging one edge of the wrapper sheet between itself and one of said frictional engaging means to positively prevent movement of the wrapper sheet longitudinally at one edge thereof during said raising, said last means comprising a cam, an engaging member, and a linkage between the cam and engaging member for moving the engaging member into contact with one edge of the wrapper sheet, said engaging member extending through said table and being raised above the level of the table by said cam and linkage.
